(57) **CLAIM**

We claim the ornamental design for an automotive vehicle exterior mirror, as shown and described.

DESCRIPTION

FIG. 1 is a front-perspective view of an automotive vehicle exterior mirror, of the new design;
FIG. 2 is a rear-perspective view thereof;
FIG. 3 is a rear view thereof;
FIG. 4 is a front view thereof;
FIG. 5 is a top view thereof;
FIG. 6 is a side view thereof;
FIG. 7 is a side view thereof, opposite that of FIG. 6; and,
FIG. 8 is a bottom view thereof.
The broken, dashed lines indicate portions therein which form no part of the claimed design.

1 Claim, 5 Drawing Sheets
